Ind., assignors to Electrolux Servel Corpora-
tion, New York, N. Y., a corporation of Dela-
ware

Application May 16, 1931. Serial No. 537,662

8 Claims. (Cl. 62—95)

This invention relates to refrigeration and more particularly to a secondary cooling element for absorption type refrigerating apparatus.

It is an object of this invention to provide a secondary cooling system comprising a single element having an evaporating portion surrounding a freezing chamber and a condensing portion adapted to be arranged in heat exchange relation with the primary evaporator of a refrigerating unit.

Another object of this invention is to provide a secondary cooling element fabricated of pressed metal sheets thereby presenting finesse in appearance, ease in manufacture, and simplicity in structure.

Other objects and advantages will be apparent from the following description taken in connection with the accompanying drawings, in which

Fig. 1 is a front elevation partly broken away of an evaporator contemplated by this invention;

Fig. 2, a section of the evaporator taken on line 2—2 of Fig. 1;

Fig. 3, a top view of the evaporator;

Fig. 4, a section taken on line 4—4 of Fig. 2;

25 and

Fig. 5, a section taken on line 5—5 in Fig. 4.

Referring to the drawings, in which like reference numerals indicate like parts, a secondary evaporator is shown fabricated of several open end metal shells including an outer shell 10, an upper inner shell 11, and a plurality of lower inner shells 12, 13, and 14. The primary evaporator shown in outline is part of a refrigerating apparatus of the absorption type. The upper inner shell 11 of the secondary evaporator is adapted to fit over the primary evaporator 15 in thermal conductive relation therewith and is shown as a metal tube adapted to fit over the cylindrical primary evaporator.

40 The lower inner shells 12, 13, and 14 enclose chambers 16, 17, and 18 respectively. The upper part of the shell 12 has a configuration corresponding to the curvature of the shell 11 and is slightly spaced therefrom in any manner, for instance by a series of struck-out spacing portions 26 of the shell 12 spot welded to the under side of the shell 11 as shown. The shells, 12, 13, and 14 which are substantially rectangular in cross section cooperate to form horizontal partitions or shelves 19 and 20 which are hollow and fluid tight, which is accomplished, for instance, by corrugating the corresponding sides of the shells and welding between the corrugations and at the edges of the shells. Welding between the corrugations adds 55 mechanical strength to the structure.

The assembled inner shells are surrounded by a single outer shell 10 which is pressed to a configuration corresponding to the outline of the inner shells and slightly spaced therefrom, for instance, by corrugating the outer shell and welding to the inner shells between the corrugations. The edges of all the shells are welded together to form a fluid tight space around the shell 11 and the chambers 16, 17, and 18. If the spacing corrugations are used, as shown, a plurality of channels encircle the shell 11 and the chambers 16, 17, and 18.

For ease of fabrication the corrugations in the outer shell 10 terminate in horizontal manifolds 21 and 22 which, when the evaporator is assembled, communicate with the corrugations in that portion of the outer shell around the upper inner shell 11 through passages 23 and 24 formed by pressing the inner shell 12. The space around the chambers 16, 17, and 18 is adapted to contain a liquid refrigerant and constitutes the evaporating portion of the secondary evaporator. The refrigerant may be introduced through a charging tube 25 which is then sealed. The space around the upper inner shell 11 constitutes the condensing portion of the secondary evaporator. Heat absorbed from the chambers 16, 17, and 18 and the surrounding medium vaporizes the refrigerant in the evaporating portion and the refrigerant vapor is cooled and condensed in the condensing portion of the secondary evaporator by the transfer of heat to the primary evaporator and flows back to the evaporating portion by gravity.

45 The primary and secondary cooling elements 90 may be constructed as a unit by using the outer casing of the primary evaporator 15 as the upper inner shell 11 of the secondary element.

A convenient method to assemble the primary and secondary elements is to leave a small space 95 between the outer casing of the primary evaporator 15 and the upper inner shell 11 of the secondary element and fill in this space with some good heat-conducting material such as babbitt. By fabricating the secondary evaporator as a 100 separate element, porcelainizing, and then securing to the primary evaporator by means of babbitt or other suitable heat conducting material, it is possible to treat the secondary evaporator as a separate entity. Thus for units to be used in 105 different sized refrigerators, different sized secondary elements may be used with the same size primary element. Furthermore, heating and resulting oxidation of the primary element is 110 avoided which would occur if the secondary ele-

- ment were porcelainized with the primary element in position. Fabrication of the secondary evaporator as a separate element also avoids difficulty in welding sheet metal directly to the casting forming the primary evaporator which difficulty arises due to the difference in thickness of the metals to be joined, the outer sheet metal shell being joined before the inner element is heated sufficiently to give a good weld.
- 10 It will be obvious to those skilled in the art that various other changes may be made in the construction and arrangement without departing from the spirit of the invention and therefore the invention is not limited to what is shown in the drawings and described in the specification but only as indicated in the appended claims.
- 15 We claim:

1. A secondary cooling element comprising an open end tubular metal shell, a substantially rectangular open end metal shell slightly spaced below said tubular shell having a curved indentation in the top thereof corresponding to the curvature of said tubular shell, a plurality of substantially rectangular open end shells below 20 the first said rectangular shell, and a sheet metal plate bent around said shells, the edges of said shells and plate being welded together and said rectangular shells and plate being pressed to form a fluid tight space extending around each 25 and all of said shells.
2. A secondary cooling element comprising an open end tubular metal shell, a substantially rectangular open end metal shell spaced slightly below said tubular shell having a curved indentation in the top thereof corresponding to the curvature of the tubular shell, and a sheet metal plate bent around said shells, all of the edges of said shells and plate being welded together and said plate being pressed to form a 30 fluid tight space around said shells.
3. A secondary cooling element comprising an open end tubular metal shell, a substantially rectangular open end metal shell slightly spaced below said tubular shell having a curved indentation in the top thereof corresponding to the curvature of said tubular shell, a plurality of substantially rectangular open end shells below 35 the first said rectangular shell, and a sheet metal plate bent around said shells, the edges of said shells and plate being welded together, said plate being corrugated to form a plurality of channels extending around each and all of said shells.
4. In combination, a primary cooling element

and a secondary cooling element comprising a plurality of sheet metal plates welded together at their edges and spaced apart by corrugations in some of said plates, said plates being welded together between the corrugations forming a plurality of fluid tight channels extending around both said primary element and a freezing chamber below said primary element.

5. In combination, a primary cooling element and a secondary cooling element comprising sheet metal plates welded together at their edges and spaced apart by corrugations in some of said plates to form a plurality of passages extending around and between said primary element and a plurality of freezing chambers below said primary element.

6. A cooling element comprising, in combination, a primary evaporator having a horizontal tubular casing, and a secondary cooling element comprising an open end metal shell spaced slightly below said primary evaporator having a curved indentation in the top thereof corresponding to the curvature of the evaporator, and a metal sheet bent around said primary evaporator and said shell, all of the edges of said sheet and shell being welded together and the edges of said sheet welded to said primary evaporator forming a narrow fluid tight space around and between said primary evaporator and said shell.

7. In combination, a secondary cooling element comprising an open end tubular metal shell, a plurality of open end metal shells forming a plurality of freezing chambers below said tubular shell, and a metal plate bent around said shells, all of the edges of said shells and plate being welded together and said shells and plate being pressed such that each and all of said shells are surrounded by a fluid tight space, and a primary cooling element within said open end tubular metal shell and slightly spaced therefrom, the space being filled with a good heat conducting material.

8. In combination, a secondary cooling element comprising a plurality of open end metal shells and a metal sheet around said shells, all of the edges of said sheet and said shells being welded together, said sheet and said shells being corrugated and welded together between the corrugations to form fluid tight channels around and between said shells, and a primary cooling element within and slightly spaced from one of said shells, the space being filled with babbitt.
